COMBINED CONNECTING PLUG AND FUSE

Samuel J. Richter, New York, N. Y.

Substituted for application Serial No. 364,089,
November 2, 1940. This application September 24, 1946, Serial No. 698,903

5 Claims. (Cl. 200—115.5)

1

The present invention relates to a plug, and, more particularly, to a connecting plug having fuse means integrally associated therewith and this application constitutes a substitute for my abandoned application Serial No. 364,089, filed November 2, 1940.

It is an object of the present invention to provide a combined plug and fuse of the character described which will localize any short circuit in the part of the circuit connected by such plug and will prevent damage to or interference with any other parts of the circuit.

It is also an object of this invention to provide a combined plug and fuse of the character described having multiple fuse elements which may be easily successively arranged in circuit, whereby the device may be continuously used, without replacement, even after repeated short circuits.

It is another object of the present invention to provide a combined plug and fuse of the character described wherein the multiple fuse portion is separable from the remainder of the plug and may, therefore, be readily replaced when all of its multiple fuse elements are used up, at very little cost.

It is a further object of the present invention to provide a combined plug and fuse of the character described which is of highly simplified, economical and compact construction and, therefore, practical for use whenever the use of a connecting plug is called for.

It is a still further object of the present invention to provide a combined plug and multiple fuse which is easy to use and is of maximum safety against hazards of shock and short circuit and which possesses many other advantages and superiorities, which will become more readily apparent to those skilled in the art from the embodiment thereof which is illustrated in the accompanying drawings in which:

Fig. 1 is a top plan view of one embodiment of a combined plug and multiple fuse of the present invention, shown with a transparent cover;

Fig. 2 is a sectional view, partly in elevation, of the same;

Fig. 3 is a plan view of the same, with the fuse cover removed, illustrating the arrangement of the plug interior;

Fig. 4 is a plan view, partly broken away, of the inner face of the fuse cover;

Fig. 5 is an enlarged fragmentary view, partly in section, of the resilient contacting means between the fuse member and the connecting prong of the plug; and

Fig. 6 is a view similar to that of Fig. 5, illustrating another form of resilient brush for contacting the fuse member.

Referring more specifically to the accompanying drawing, the number 10 designates an open ended cup-like housing, which may be made of

2

any non-conductive material customarily used for devices of like character. The interior of the housing 10 may be provided with a pair of preferably oppositely disposed protrusions, forming shoulders 11. A screw seat 12 is formed in each of the shoulders 11, and a slot 13 is formed through the bottom of the housing 10, alongside each of the shoulders 11, to receive a prong 14, which has an offset portion 15, adapted to rest on the surface of the adjacent shoulder 11, and having an aperture 16, which is in register with the seat 12.

Another screw seat 17 is formed, preferably centrally, in the bottom wall 18 of the housing, in which may be arranged a binding post 19, which may be provided with a flange 20, above its threaded end, to overlie the edges of the recess 17, and which is further provided with a threaded recess 21 on its free end.

An insulating wall or partition 23, preferably integral with the housing, may be arranged between one of the prong slots 13, and the recess 17, and a pair of apertures, 24 and 25, respectively, may be formed in the side wall of the housing 10, through which individual lead wires of an electrical cable 26 may be introduced into the housing 10, one into each of the compartments formed by the wall 23. One of the lead wires is secured, in the conventional manner, between the flange 20 of the binding post 19 and the bottom wall 18 of the housing 10. The second lead wire is conventionally connected to the prong 14, on the other side of the partition 23, by means of a screw 28, which is set into the seat 12.

Electric contact between the binding post 19 and the second of the prongs 14, is provided through a cover, generally designated as 29, arranged over the opening of the housing 10. Cover 29 may comprise an outer insulating shell 30, which may, if desired, have a transparent center portion 31, which may consist of mica or other similar, suitable, transparent, non-conductive material. The shell 30 is preferably provided with depending flange 32, forming a shallow, tray-like, outer cover member, in which is arranged a layer or sheet of fusible material of the type conventionally used for fuse purposes, and formed to have a central, or hub portion 33, from which extend radiating wing portions, each comprising a narrow, easily fusible neck portion 34 and an enlarged end contact portion 35.

An inner layer or sheet 36, of insulating material, preferably of the low cost variety, such as cardboard, or the like, is arranged over and preferably secured to the fusible layer and over the edge of the flange 32 of the shell 30.

Registering apertures are provided through the center of each of the three layers of the cover 29, to form a continuous aperture 37, through which a screw 38, having, preferably, a knurled, insu-

lated head 39 secured to the screw in any suitable manner, is freely inserted, with its head 39 engaging the edges of the aperture 37. The lower end of the screw 38 is engaged in the threaded recess 21 of the binding post 19 to retain the cover rotatably on the housing. The upper portion 42 of the screw may be enlarged or thickened to fit snugly within the aperture 37 so as to make electrical contact with the inner edge of the fuse layer 33, to thereby complete the circuit between the fuse and the binding post 19.

To insure contact between the fuse layer and the enlarged portion 42 of the screw 38, a portion of the fuse material about the opening 37 may be folded over inwardly, over the edge of the aperture, through the inner insulating layer 36, to thereby provide a substantial area to contact between the fuse layer and the screw 38.

A plurality of apertures 44 are formed in the inner insulating layer 36, corresponding in number to the wing ends 35, and arranged to expose said wing ends 35 to the interior of the housing.

To complete the circuit between the fuse layer to the second of the prongs 14, brush means may be provided, connected to the said second prong. Such brush means may be, preferably, of a resilient nature and may comprise a brush member 45 mounted fixedly on one end of a spring element 46, which may be secured in the conventional manner to the said prong 14, as by means of a contact screw 47, set into the corresponding screw seat provided in the end face of the said prong.

If desired, the brush may be of integral construction, in the form of a resilient conductor 48, as illustrated in Fig. 5 of the drawing, so that the necessity for a separate spring is eliminated.

The brush portion of either brush 45 or 48 is so disposed as to register, at all times, with one of the apertures 44, and may be preferably disposed at an angle to the cover 29, substantially parallel to the side of the housing, so as to permit rotation of the cover only in one direction, the direction of the upward incline of the brush, and to prevent its rotation in an opposite direction. Thereby, contact is assured between the brush and successive, unused fuse wings, as the cover is turned.

This completes a description of one embodiment of the combined plug and fuse of the present invention. It is to be understood that such embodiment is shown and described for purposes of illustration only, and that it is not intended to limit this invention to the details thereof as, obviously, many variations and modifications thereof may be made within the spirit and scope of the invention and the claims hereto appended.

What I claim is:

1. In a connecting plug of the character described, a cup shaped housing having a threaded recess therewithin, a binding post having a threaded recess in its end arranged within the threaded recess in the housing, and a cover arranged over the open end of the said housing, said cover having a layer of fusible material having exposed portions, a screw passing freely through the said cover contacting the said layer of fusible material and engaging within the threaded recess in the said binding post to permit free rotation of the cover over the said housing.

2. In a connecting plug of the character described, a cup shaped housing, said housing hav-

ing slots in its bottom wall and an opening in its side wall, connecting prongs arranged within the said slots, a binding post having a recessed end arranged within the housing, wires passing through the said opening in the side wall of the housing, one of said wires electrically connected to one of the said prongs, the other of the said wires electrically connected to the said binding post, a cover having multiple fuse elements arranged on the said housing, each of said fuse elements being in contact with the said binding post, and a brush on the other of said prongs in contact with one of said fuse elements.

3. In a connecting plug of the character described, a housing, a pair of prongs passing through the wall of said housing, a pair of binding posts in the said housing, one of the said binding posts in electrical contact with one of said prongs, a cover rotatably mounted over the said housing, said cover having a layer of fuse material including a plurality of radially formed wings, a screw passing through the said cover in electrical contact with the said fuse material and engaged on the said binding post, a brush connected to the other of the said prongs and arranged to engage a radiating wing of the said fuse material.

4. In a connecting plug of the character described, a housing, a pair of prongs passing through the wall of the said housing, said housing having an open end, a binding post arranged within the said housing, said binding post having a threaded recess in its end, a cover arranged over the opening of the said housing, said cover comprising an exterior layer of insulating material, an intermediate layer of fusible material, said intermediate layer formed to have a central portion and a plurality of radiating wing portions, and an inner layer of insulating material, said inner layer having a plurality of circularly arranged apertures, each adapted to expose one of the wing portions of the said intermediate fusible layer, a screw passing through said cover, in electrical contact with the central portion of said intermediate fusible layer and set in the threaded recess of said binding post, a brush member resiliently connected to one of said prongs, in register with the said circular row of apertures, to contact the inner fusible layer of the cover, whereby the said cover may be turned to contact the several wings of the fusible layer, one at a time.

5. The structure of claim 4, in which the brush member is arranged at an angle to the cover, in a direction tangential to the circular row of apertures, whereby said cover may be turned in one direction only, to permit contact by the said brush member with successively arranged wings of the layer of fusible material.
